UNITED STATES PATENT OFFICE

2,495,742

SEAL SUPPORT FOR FLOATING
ROOF TANKSMichael N. Lebedeff, Chicago, Ill., assignor to
Chicago Bridge & Iron Company, a corporation
of Illinois

Application May 15, 1946, Serial No. 669,905

3 Claims. (Cl. 220—26)

1

This invention relates to a seal support, and particularly to a support for a secondary seal to be used above a principal sealing member in contact with the shell of a floating roof tank.

Floating roof tanks comprise a shell and a floating roof therein adapted to float on top of the stored liquid within the shell and rise and fall as the quantity of stored liquid is increased and decreased. In order to prevent contamination of the liquid by rain, dirt, and the like, and to reduce evaporation losses, it is necessary that a sealing means be provided between the roof and the shell of the tank. An efficient sealing means has been found to be a flat plate-like member that is supported from the roof and held against the shell of the tank. Flexible sealing means, usually comprised of a fabric impregnated with an impervious, flexible material such as synthetic rubber are provided connecting the flat sealing member and the roof. As the flat sealing member is usually rather heavy and therefore does not form a perfect seal with the shell of the tank, it has been found advisable to provide a secondary sealing member located above the first sealing member. We have invented an improved secondary sealing member comprising broadly a substantially flat metal sheet to be held against the shell above the first sealing member.

The invention also includes the improved means for supporting both sealing members from the roof so that substantially uniform pressure may be applied to the sealing members around the entire circumference of the shell of the tank in order to hold the sealing members in close contact with the shell.

The invention will be described as related to the embodiment shown in the accompanying drawings. Of the drawings Fig. 1 is a fragmentary plan view of a floating roof tank including the new secondary sealing member and the new support for both the first and secondary sealing members; Fig. 2 is a vertical section taken along line 2—2 of Fig. 1; Fig. 3 is a vertical section taken along line 3—3 of Fig. 2; and Fig. 4 is an elevation of an improved washer bar for holding the flexible sealing member in contact with the first sealing member.

In the drawings the tank comprises a substantially cylindrical shell 10, a floating roof 11 therein, a flat sheet metal first sealing member 12 held against the shell 10, a flat metal secondary sealing member 13 also held against the shell and located above the first sealing member 12, and support means 14 for supporting all sealing members.

2

The secondary sealing member 13 comprises a strip of flat sheet metal having its top edge 15 and bottom edge 16 bent back from the vertical. The sheet metal strip, which is preferably stainless steel, is provided with spaced vertical flexures 17 formed of inwardly directed folds in the metal. These flexures permit the secondary seal to expand and contract. The top edge 15 of the secondary seal is provided with spaced vertical slits 18.

The support means 14 comprises upstanding bolts 19 attached to the roof of the deck, a flat plate 20 adjustably mounted on these bolts by the top nuts 21 and bottom nuts 22, an upstanding first pipe 23 supported on the plate 20, a horizontal second pipe 24 attached near its front end to the first pipe 23, and a third pipe 25 of smaller diameter than the second pipe extending through the second pipe. There is provided a spring 26 between the plate 20 and the second pipe 24. This assembly is described and claimed in our copending application Serial No. 637,017, filed December 22, 1945, and the Henry O. Wilbur copending application Serial No. 637,016, filed December 22, 1945.

The front end 27 of the pipe 25 is flattened horizontally and extends through an opening 28 in a spreader bar 29. The spreader bar 29 is a steel channel with the ends of the channel extending toward the shell of the tank. The spreader bar 29 is held in place by means of a vertical bolt 30 extending through the channel and the flattened end 27. This bolt has its bottom end extending below the channel and is provided with a head 31 with a compression spring 32 between the head and the lower portion of the channel.

At each end of the first spreader bar 29 there is located a smaller, second spreader bar 33, also formed of a steel channel of smaller width than the channel of the first spreader bar, so as to fit within the ends of the first spreader bar. Each second spreader bar is held at substantially its center by bolts 34 extending through the sides of the channels. The first spreader bar 29 is rotatably mounted around its bolt 30, and both of the second spreader bars 33 are rotatable around their bolts 34.

The first sheet metal sealing member 12 is preferably but not necessarily made according to our copending application Serial No. 636,442, filed December 21, 1945. It is provided with an inwardly extending top marginal area 35 and an outwardly turned edge 36 to provide a smooth, non-cutting edge portion. There is provided a flexible sealing member 37 extending from the

top edge of the roof 11 to the top of the first sealing member 12 and on to the bottom edge 16 of the secondary sealing member 13. This flexible sealing member may be a fabric impregnated with an impervious solid material, such as a synthetic rubber. It is fastened to the roof by means of a flat washer bar 38 held in place by a series of bolts 39, and is held in contact with the top of the first sealing member 12 by means of a substantially U-shaped washer bar 40 bolted by means of bolts 41 to the top of the first sealing member 12. The top edge of the flexible sealing member 37 is fastened to the bottom edge 16 of the secondary sealing member 13 by means of a second flat washer bar 42.

The U-shaped washer bar 40 has its legs 43 extended toward the shell of the tank and contacting the flexible sealing member 37. The base 44 of this washer bar is substantially flat and is provided with spaced transverse slots to give flexibility to the U-shaped washer bar 40. The washer bar is provided with inwardly extending brackets 45 engaging bolts 46 passing through the ends of the second spreader bars 33.

In order to support the secondary sealing member 13 there are provided upstanding arms 47 at each end of each second spreader bar 33. Each arm 47 is provided with a curved leaf spring 48 at its top end with the leaf spring being arranged in horizontal position and each end of each leaf spring passing through a slot 49 in a vertical flexure 17. There is one spring 47 provided for each pair of adjacent flexures 17 and each spring is so arranged that it serves to press the secondary sealing member out against the shell.

When the seal and seal support are assembled the effective distance between the two ends of each second spreader bar 33 is substantially equal to the distance between adjacent ends of each adjacent pair of second spreader bars. Similarly the effective distance between the ends of each leaf spring 48 is substantially equal to the distance between adjacent ends of each adjacent pair of leaf springs. The vertical flexures 17, therefore, are equally spaced around the secondary sealing member 13.

As shown in the drawings, the supports 14 are mounted on the top deck 50 of the floating roof 11 and the roof is provided with a brace 51 under each support. If a roof is used that has no top

deck the supports may rest on plates or other structural members extending across portions of the top of the roof.

Having described the invention as related to the embodiment set out in the accompanying drawings, it is intended that the invention be not limited by any of the details of description unless otherwise specified, but rather be construed broadly within its spirit and scope as set out in the accompanying claims.

Claims:

1. In a floating roof tank comprising a shell, a floating roof therein, a metal sealing means having a substantially flat portion adapted to be held in sealing relationship with the shell, and support means for supporting the sealing means including a member supported on the roof extending toward the shell, an upstanding arm supported by the extending member and a substantially horizontally arranged leaf spring supported at substantially its center by the arm the ends of said spring supporting said portion of the sealing means and normally holding said portion against the shell by the spring action.

2. In a floating roof tank comprising a shell, a floating roof therein, sealing means held in sealing relationship with the shell including a flat sheet metal plate having vertical flexures therein, and support means for supporting the sealing means including a member supported on the roof extending toward the shell, an upstanding arm supported by the extending member and a substantially horizontal leaf spring carried by the arm and supported at its center with the ends of the arm supporting the sheet metal plate at a pair of said flexures.

3. The support means of claim 2 wherein the flexures are folds in the sheet metal extending at substantially right angles to the body of the sheet metal and the ends of the spring are held in slots provided in the folds.
